UNITED STATES PATENT OFFICE.

JOSEPH H. ATWATER, OF PROVIDENCE, RHODE ISLAND.

COPYING-PRESS.

Specification forming part of Letters Patent No. 37,379, dated January 13, 1853.

To all whom it may concern:

Be it known that I, JOSEPH H. ATWATER, of the city and county of Providence, and State of Rhode Island, have invented a new, useful, and Improved Copying-Press; and I do hereby declare that the same is described and represented in the following specifications and drawings.

To enable others skilled in the art to make and use my invention, I will proceed to describe its construction and the mode of using it, referring to the drawings, in which the same letters indicate like parts in each of the figures.

Figure 1 is a top view of my improved press. Fig. 2 is a view of the press open. Fig. 3 is a section on the lines zz , Figs. 1 and 2.

The nature of my invention consists in the improvements described in the following specification.

In the accompanying drawings, A is the top and B the bottom plates of the copying-press, and are each provided with sides C C, and ends D D, forming two open boxes, which, when closed, as shown in Figs. 1 and 3, form a case to protect the book E, as shown in the latter figure. The plates or boxes A and B are connected together with strong hinges F F, which form the fulcrum of the two boxes, which act on the copy-book like two levers when applied to it to take a copy. I apply a spring-catch, G, to the plate A, so that when the plates are pressed together in taking a copy, the catch G will spring into the stand H on the plate B and lock the two together, so as to leave the book in press as long as may be required to take a copy, and with good ink and good paper I have taken a perfect copy by keeping the press closed only thirty seconds or half a minute.

In order to lock up the book and press when not in use, I put a lock at I and a catch at J for that purpose.

In order to adapt this press to books varying in thickness I make a movable plate or platen, K, just wide enough to traverse freely in the box and a little shorter than the length of the box inside, but as long as the book used. On the under side of the plate K, I fasten two or more inclined planes, L L, and make the same number of inclined planes M in or on the bottom B, so that the plate K may be adjusted on these inclined planes to suit the thickness of the book used in taking

copies. I fasten a small stand or thumb-piece, N, to the plate K, by which it may be adjusted on the inclined planes, which are not smooth and steep enough to let the plate K slip when the pressure is applied to the copy-book. I make a scale, P, on the plate K and fasten an index or stand, Q, to the inside of the side C, so that when it is ascertained in what position it will give sufficient pressure to take a copy with any particular book the book may be marked, the number indicated by the index on the scale, and the plate set to the number of the book whenever it is used.

To take a copy with this press, place the copying-book on the platen K, with its end against the stand N and its edge against the stand Q, and adjust the platen so that about one hundred pounds pressure on the end of the top A farthest from the hinges will bring the top down so that the bolt G will spring into the stand H and fasten it down. Let it remain thirty seconds, draw back the bolt, open the press, and take out the book and the copy will be complete.

My improved press costs about half as much as an iron press. It is portable, durable, convenient, and light, and it copies as well and as quickly as any other press, however costly or cumbrous. It keeps the copying-book clean and safe. It is easily moved from one place to another, or carried in a trunk when traveling, as it weighs only about five pounds. It occupies very little room and requires no expense to set it up so that it can be worked. It is not liable to break down or blur in copying, and is every way more convenient than the iron presses in common use.

I believe I have described and represented my improved copying-press so as to enable any person skilled in the art to make and use it without further invention or experiment.

I will now state what I desire to secure by Letters Patent—to wit:

I claim—

A box copying-press, for the purpose of taking a copy of writing and for the protection and safe-keeping of the copying-book, as herein described.

JOSEPH H. ATWATER.
